UNITED STATES PATENT OFFICE.

BERTHA CROWE, OF BROAD RUN, VIRGINIA.

FOOT APPLIANCE FOR THE TREATMENT OF BUNIONS.

1,175,718.

Specification of Letters Patent. Patented Mar. 14, 1916.

Application filed May 24, 1915. Serial No. 30,125.

To all whom it may concern:

Be it known that I, BERTHA CROWE, a subject of the King of Great Britain, residing at Broad Run, in the county of Fauquier and State of Virginia, have invented new and useful Improvements in Foot Appliances for the Treatment of Bunions, of which the following is a specification.

This invention relates to devices for the relief and treatment of bunions, and it has for its object to produce a simple and effective device of this class which may be worn in the day time and which will not only tend to relieve the pain caused by pressure upon the inflamed joint, but will also tend to alleviate and to cure the affliction.

A further object of the invention is to produce a device of the class described which is in the nature of an attachment to a shoe, and which will be thereby held securely in the desired position to obtain the best results.

With these and other ends in view which will readily appear as the nature of the invention is better understood, the same consists in the improved construction and novel arrangement and combination of parts which will be hereinafter fully described and particularly pointed out in the claims.

In the accompanying drawing has been illustrated a simple and preferred form of the invention, it being, however, understood that no limitation is necessarily made to the precise structural details therein exhibited, but that changes, alterations and modifications within the scope of the claims may be resorted to when desired.

In the drawing, Figure 1 is a perspective view showing a portion of a human foot to which a part of the improved device has been applied. Fig. 2 is a perspective view of a shoe to which the remaining part of the device has been applied. Fig. 3 is a sectional view taken horizontally through a shoe and indicating therein a foot to which the device has been applied. Fig. 4 is a sectional detail view taken on the line 4—4 in Fig. 3.

Corresponding parts in the several figures are denoted by like characters of reference.

The improved device or appliance comprises a hood 15 adapted to receive the big toe and a portion of the foot, said hood being of a length to extend over the metatarsophalangeal joint. The hood which

may be made of muslin or other suitable material may be provided with a lining member 16 of soft leather, chamois skin or the like, and it has a foot encircling strap 17. The hood is also provided at its outer edge portion with a rearwardly extending strap 18 adapted to be adjustably connected with an attaching member, such as a buckle 19, carried by a strap 20 which is securely attached by stitching or in some other convenient manner to the counter or heel portion 21 of a shoe.

Within the hood I prefer to place a pad P of felt or other suitable soft and resilient material, said pad having a thick front portion 23 adapted to lie in front of the toe and relatively thin bottom portion 24 that extends beneath the toe, the purpose being to relieve the toe nail from undue pressure.

In operation, the hood 15 is applied to the big toe, the strap 17 forming a loop that passes around the foot. The stocking, a portion of which is shown at S, is provided with a slit 25 for the passage of the strap 18, which latter after the shoe has been drawn on the foot is connected with the strap 20 by the buckle 19, which latter permits of adjustment whereby the desired degree of tension may be obtained. It will be readily seen that the tension thus caused will operate to draw the big toe outward, thereby straightening the joint and causing it to remain in its natural position.

The use of this appliance has proven in practice not only to reduce the unsightly appearance caused by a bunion, but also to greatly relieve the pain caused by the pressure of the shoe against the inflamed portion of the foot. It is believed that when resorted to in time, the use of the appliance will ultimately effect a complete cure of the diseased condition known as a bunion.

The device, as will be seen, is extremely simple and inexpensive, and that portion which is worn on the foot may be made of washable material and may also be easily renewed at small expense. It may thus be easily kept in a clean and sanitary condition.

It will be particularly noted that the tension on the big toe is produced by a stress on the hood in a direct rearward direction, and not as is the case in some devices by a lateral strain exercised by means of a splint or

spring bound on the side of the foot. Such lateral strain cannot be exerted without a direct pressure on the bunion or inflamed portion which is always uncomfortable and sometimes unendurable. In this device the stress on the hood is in the rearward direction and this produces an outward tension on the big toe without direct pressure on the bunion, thus producing a curative effect without discomfort.

Having thus described the invention, what is claimed as new, is:

1. A foot appliance comprising a hood applicable to the big toe and having a rearwardly extending strap, in combination with a shoe having a strap attached interiorly on the heel portion thereof and extending forwardly, said last mentioned strap having a connecting member for ad-

justable connection with the strap extending from the hood.

2. A foot appliance comprising a hood applicable to the big toe and having a rearwardly extending strap, in combination with a shoe having a strap attached interiorly on the heel portion thereof and extending forwardly, said last mentioned strap having a connecting member for adjustable connection with the strap extending from the hood, and a stocking having a slit for the passage of the strap extending from the hood.

In testimony whereof I affix my signature in presence of two witnesses.

BERTHA CROWE.
